UNITED STATES PATENT OFFICE.

LOUIS STEINBERGER, OF BROOKLYN, NEW YORK.

HIGH-VOLTAGE STRAIN-INSULATOR.

1,054,148.

Specification of Letters Patent. Patented Feb. 25, 1913.

Original application filed April 4, 1910, Serial No. 553,216. Divided and this application filed May 17, 1912. Serial No. 698,009.

To all whom it may concern:

Be it known that I, LOUIS STEINBERGER, residing at Brooklyn, in the county of Kings and State of New York, have invented certain new and useful Improvements in High-Voltage Strain-Insulators, of which the following is a specification.

This invention relates to strain insulators for high voltage electric conductors, such as that illustrated in my pending application, Serial No. 553,216, filed April 4th, 1910, of which this is a division and is adapted for use in various relations and for various purposes, such as power transmission; and for guy wires, or cables employed as stays for towers, or for poles, masts and other supports, in wireless telegraphy and telephony, as well as in ordinary commercial work.

I seek, among other things, to provide an insulator which is compact and extremely simple in construction, which may be manufactured at low cost, and which is capable of withstanding a considerable mechanical stress and very high voltages, the insulator thus being, as far as practicable, proof against the evils of leakage, arcing and puncturing.

Among the purposes sought to be accomplished by the aid of my invention are the following; I. To provide an insulator possessing the highest possible form of electric insulation combined with greatest mechanical strength. II. To provide certain internal parts of the structure with members for resisting and distributing mechanical stresses.

III. To provide certain internal parts of the structure with hollow members to operate in conjunction with the strain members. IV. To provide a body of insulating material having metallic tension members extending a considerable distance into it from opposite ends and crossing each other within the body of insulating material. V. To provide tension members with fastening means of such conformity as to enable one to attach or remove them at will. VI. To strengthen the body of insulating material by reinforcing the same in the vicinity of where the tension members cross each other, the reinforcing material thus added serving also the additional purpose of preventing arcing over from one tension member to the other. VII. To provide within the body of insulating material a metallic member having generally the form of a semi-ring for gripping against a portion of the insulator

body, and tension members detachably connected with the ends of said semi-ring for exerting thereupon the mechanical strain to which the insulator is subjected. VIII. To connect the tension members, just mentioned, with a plate engaging one end of the insulator body and provided with an eye for enabling the insulator body to be suspended. IX. To protect from the weather, a portion of the insulating member, terminal, conductor or guy, as the case may be, which may be employed in connection with the insulator. X. To give the various parts such conformity as will tend to prevent leakage, arcing, or puncturing under the influence of currents of high potential, and to adapt the device for application in various relations.

Other objects and aims of the invention, more or less broad than those indicated, together with the advantages inherent, will be in part obvious and in part specifically referred to in the course of the following description of the elements, combinations, arrangements of parts, and applications of principles constituting the invention; and the scope of protection contemplated will appear in the claims.

In the accompanying drawing, which is to be taken as a part of this specification, and in which I have shown a merely illustrative embodiment of the invention: Figure 1 is a central, longitudinal, sectional view, through an insulator constructed in accordance with this invention; Fig. 2 is a view similar to that shown in Fig. 1, but being taken on a plane at right angles to the plane of Fig. 1; Fig. 3 is a transverse, sectional view taken substantially on the plane of line III—III of Fig. 1; Fig. 4 is an end, elevational view of the insulator; and Fig. 5 is a detail, perspective view of a hollow metallic semi-ring, employed in the body of the insulator, and which I designate, for convenience, a stirrup.

Referring to the drawings by numerals, 1 indicates the body of the insulator which may be of any suitable material, such as porcelain or "Electrose". The body of the insulator has generally the form of a solid cylinder formed exteriorly with a series of annular corrugations 2.

Extending inwardly from one end of the body portion 1 are a pair of spaced parallelly disposed passage-ways 3, which terminate approximately at a point midway between

the opposite ends of the insulator. A metallic, preferably hollow, member 4, of semi-ring, or U-shape, is embedded in the material of the insulator in such manner that the opposite open ends thereof are alined with the passage-ways 3. This member 4, because of its particular office, I prefer to designate as a stirrup. The opposite ends of the stirrup are straightened into parallelism, as at 20, and said straightened portions are preferably internally threaded and adapted to engage and hold a pair of tension members such as the bolts 5 which extend through the passage-ways 3 and have their inner ends threaded into the threaded open ends of the stirrup. The bolts 5 extend through suitable apertures formed in a disk 6, fitting over the end of the body portion of the insulator, and said bolts are formed with substantial heads 7, outside of said disk, whereby said disk is held firmly and securely in position relatively to the body portion of the insulator. Formed integrally with the disk 6 is an extension 7 comprising an eye 9. The eye 9 obviously is positioned in such manner as to be in the line of greatest stress longitudinally of the body portion of the insulator, that is, midway between the planes of the bolts 5.

30 Extending inwardly from the opposite end of the body portion of the insulator are a pair of passage-ways 10 which terminate approximately midway between the ends of the insulator. The relative disposition of the 35 two sets of passage-ways 3 and 10 is such that a plane intersecting the longitudinal axes of the passage-ways 10 is approximately at right angles to a plane intersecting the longitudinal axes of the passage ways 3. The inner ends of the passage ways 10 may be brought into communication by a stirrup piece similar to that described for connecting the inner ends of the passage ways 3, or the inner ends of passage ways 10 40 may be connected by a stirrup member, as 11, which has its opposite end portions continued straight throughout the extent of the passage ways 10 and adapted to receive a separately formed, preferably flexible, tension member as 12, if desired, in which instance the outer or free ends of the tension member 12 will be suitably connected and reinforced by a clamp casting 13 forming an eye 14 for use in the same capacity as is the 55 eye 19.

The two stirrup portions are arranged so as to link one within the other with a considerable portion of insulating material of the body portion of the insulator interposed between all parts of said stirrup members.

It will be noted that the only stress to which the insulator is actually subjected is a compression stress tending to force the hollows of the two stirrup members toward 60 each other. This structure possesses except-

tionally great mechanical strength combined with the highest possible form of electric insulation.

The action of the bolts 5 and the stirrup 4, being rigidly connected together in use, is such as to effectively distribute the mechanical strains applied to the eye 9. The stirrup, also, because of its form as a semi-ring, and further because of its being hollow and made of thin metal, can undergo slight degrees of distortion and in so doing is caused to fit more neatly against the adjacent portions of the body of the insulator. The strain upon the eye 9 is transferred into a direct straight path on the bolts 5 in the direction of the longitudinal axes thereof and is thus applied with equal force to the opposite ends of the stirrup, and when of sufficient severity or of sudden application, the stirrup gives slightly and this effects such an admirable distribution of strains upon contacting parts of the insulator body as to materially decrease the likelihood of fracture of the insulator.

The bolts 5 are readily detachable from their engagement with the stirrup, for the purpose of renewing the bolts or the disk which they secure, as when one of the heads 7 is found defective, the eye 9 worn, or for any other reason.

At the point where the greatest strain is present in the insulator, and because of the increased diameter of the stirrup over the ends of the tension bolts, the body portion of the insulator is somewhat enlarged as 100 at 15 for strengthening the insulator to resist such strain.

Formed upon the two ends of the body portion 1 are annular flaring collars 16 which serve to shelter the metallic parts contained within them and thereby protecting the same from undue exposure to the weather. It will be noted that the outer ends of the collar 16 extend fully to the outermost limits of the lug and clamp 14, 110 so that the innermost portions of the collars are always dry and dry spaces are always present adjacent the various metallic parts nearest the body portion of the end of the insulator.

Owing to the novel structure of my strain insulator, it will be observed that for any given zone of insulation body, it provides the greatest possible insulating surface for the prevention of surface leakage and also 120 the tendency to arc and to puncture, thereby producing a very large factor of safety.

These insulators may be used separately or any number of them may be linked or connected together, or connected to insulators of different form, in any preferred manner so as to increase the aggregate insulation for supporting a line, dead ending, guying or any other relation where currents of very high potential are employed.

As many changes could be made in the above construction and many apparently widely different embodiments of this invention could be made without departing 5 from the scope thereof, it is intended that all matter contained in the above description or shown in the accompanying drawing shall be interpreted as illustrative and not in a limiting sense.

10 It is also to be understood that the language used in the following claims is intended to cover all of the generic and specific features of the invention herein described and all statements of the scope of 15 the invention, which as a matter of language, might be said to fall therebetween.

Having thus described my invention what I claim as new and desire to secure by Letters Patent, is:

20 1. A high potential strain insulator, comprising a body of insulating material, a stirrup embedded permanently therein, and tension members detachably connected with opposite ends of said stirrup and extending 25 to the same end of said body of insulating material.

2. A high potential strain insulator, comprising a body of insulating material, a stirrup mounted therein and having generally the form of a semi-ring, and longitudinal tension members detachably connected with opposite ends of said semi-ring and extending to the same end of said body of insulating material.

35 3. A high potential strain insulator, comprising a body member of insulating material, a stirrup embedded therein and having substantially the form of a hollow semi-ring provided at its ends with threads, bolts 40 extending straight into said body portion and having threads mating said threads of said semi-ring, and an eye connected with said body member by aid of said bolts.

4. A high voltage strain insulator, comprising a body of insulating material, a stirrup embedded therein, a plurality of tension members extending into said body of insulating material and engaging said stirrup, said tension members being provided with heads, and a plate disposed between said heads and said body of insulating material.

5. A high voltage insulator, comprising a body member of insulating material provided with a plurality of passages extending thereinto, a stirrup disposed within said body member and partially bounding said passages, and tension members having portions extending into said passages and secured to said stirrup.

6. A high potential strain insulator, comprising a body member of insulating material, provided with straight passages ex-

tending thereinto, a resilient stirrup disposed within said body member and reached 65 by said passages, and means extending into said passages and co-acting with said stirrup for supporting said body member.

7. A high voltage insulator, comprising a body member of insulating material provided with a passage extending thereinto, a resilient tubular stirrup disposed within said body member and partially bounding said passage, and tension mechanism engaging said stirrup and extending through said 75 passage for supporting said body member.

8. As an article of manufacture, a high voltage insulator, comprising a body portion of insulating material provided with substantially parallel passages extending 80 into said body portion from opposite ends thereof and reaching beyond the center of said body portion, the passages from each end being connected within said body portion so as to form continuous but separate 85 passages located entirely within said body portion, a resilient anchoring member at the inner end of one of said passages and a tension member extending through said passage, and being connected with said resilient anchoring member.

9. A high voltage strain insulator, comprising a body member of insulating material provided with a passage of substantially semi-circular form in general outline, 95 and further provided with a pair of straight passages parallel with each other and merging into said first-mentioned passage, all of said passages being disposed completely within said body member, and a pair of straight bolts each having a portion extending through one of said straight passages, said bolts being connected with said hollow member.

10. A high voltage insulator comprising 105 a body portion of insulating material formed with substantially parallel passages extending thereinto from opposite ends, and reaching beyond the center of said body portion, the passages from the same end being 110 connected together within said body portion so as to form a continuous passage having spaced legs located entirely within said body portion, a resilient anchoring member at the inner end of one of said continuous passages, 115 and a plurality of strain members one in each of the legs of said continuous passage engaging said resilient anchoring member at spaced localities thereon.

In testimony whereof I affix my signature 120 in the presence of two witnesses.

LOUIS STEINBERGER.
